VARIABLE CONDENSER.

Application filed January 7, 1925. Serial No. 1,067.

My invention relates to variable condensers, and a purpose of my invention is the provision of a variable condenser which is a mica condenser in the true meaning of the term in that it embodies a di-electric element which has direct contact with the plates or conducting elements of the condenser to the exclusion of air, and in such manner that the area of contact between the elements can be varied at will to effect a variation in the capacity of the condenser.

It is also a purpose of my invention to provide a variable condenser of the above described character in which one of the conducting elements has rolling contact with the di-electric element in effecting a variance in the area of contact between the elements whereby the possibility of injury to the di-electric usually caused by friction between the elements is entirely eliminated.

A further purpose of my invention is the provision of a variable condenser in which the elements thereof are arranged to prevent reduction of body capacity and to permit a small variance in the capacity by increasing or decreasing the pressure between certain of the elements.

I will describe only one form of variable condenser embodying my invention and will then point out the novel features thereof in claims.

In the accompanying drawings,

Figure 1 is a vertical sectional view taken on the line 1—1 of Figure 2;

Figure 2 is a diametrical section taken on the line 2—2 of Figure 1;

Figure 3 is a view showing the inner side of the condenser;

Figure 4 is a view similar to Figure 2, with parts of the condenser in elevation;

Figure 5 is a detail perspective view of the stationary conducting element embodied in the condenser.

Referring specifically to the drawings, in which similar reference characters refer to similar parts in each of the views, my invention, in its present embodiment, comprises a stator or stationary body 15 formed of insulating material and adapted to be secured to the outer side of a panel 16 constituting a portion of the casing for a radio receiving set. In the present instance, I have shown tubular studs 17 extending into the panel 16 and interiorly threaded to receive screws 18 which extend through the stator 15, with their heads disposed in con-

ducting cups 19 reposing within suitable pockets formed in the stator. The screws 18 co-operate with nuts 20 exteriorly threaded on the stud 17 in securing the stator as a unit to the outer side of the panel. The studs 17 also receive binding screws 21 to which conductors (not shown) are adapted to be connected.

The stator 15 in the present instance is of disk form, and mounted upon its periphery is a split annulus 22 formed of copper or other suitable material and which constitutes the stationary conducting element of the condenser. As shown in Figures 1 and 5, this conducting element is provided with an extension 23 projecting into a suitable slot formed in the stator 15 for contact with one of the conducting cups 19 so as to provide an electrical connection between the conducting element and the corresponding screw 18. Surrounding and contiguous to the stationary conducting element is a split annulus 24 formed of mica and constituting the di-electric of the condenser. This mica annulus is in the form of a strip with its ends 24^a extending into a suitable slot formed in the stator 15 diametrically disposed with respect to the slot receiving the extension 23, as clearly shown in Figure 1.

Preferably formed integrally with the stator 15 is a gear 25 constantly meshing with a smaller gear or pinion 26 having a hub 26^a rotatably mounted on a screw including a shank 27, a head 28 threaded in a collar 29, and a conical portion 30 connecting the head and shank. The collar 29 is fixedly secured within a rotor including a body 31 of insulating material and constituting a handle for operating a graduated dial 32 connected to the handle through the medium of an annular flange 33. It is to be understood that the flange and dial are formed of insulating material, and that the threaded collar 29 is mounted in the flange, as clearly shown in Figures 2 and 4. The rotor as a unit is rotatably mounted on the stator and to this end a stub axle 34 extends axially through the stator 15 and is rotatably held by means of a nut 35 threadedly engaging the stub axle and disposed within a suitable recess formed on the inner side of the stator. The stub axle is of such length that it projects from the stator and is fixedly received within a suitable opening 36 formed in the rotor, whereby the rotor is rotatably supported.

The hub 26^a of the gear or pinion 26 has attached thereto one end of a strip or ribbon 37 of copper which constitutes the movable conducting element of the condenser, the other end of the strip being secured between the in-turned ends 24^a of the di-electric and having electrical contact with the other conducting cup 18 so as to be in electrical communication with the corresponding binding 10 screw 21.

In practice, the stator of the condenser may be readily applied to and firmly secured upon the outer side of the panel 16, a cover plate 38 being interposed between the panel 15 and stator, as clearly shown in Figure 2. In Figure 1 I have shown a di-electric 37 completely unwound from the hub 26^a, which in reality constitutes a reel, so that substantially its entire length is in direct contact 20 with the di-electric 24, thus producing the greatest capacity of which the condenser is capable. To reduce the capacity of the condenser, the rotor is rotated to the right as when viewed in Figure 1, and the hub 26^a 25 being carried thereby and meshing with the gear 25, it will be clear that the gear not only moves bodily about the axis of the stator as a center, but it rotates about the shank 27 as a center, thereby winding upon 30 itself the movable conducting element 37. As the movable conducting element is wound upon the hub 26^a, it will be manifest that it is moved out of contact with the di-electric 24, thus operating to reduce the capacity of the condenser in direct proportion 35 to the amount of the conducting element moved out of contact with the di-electric. It is to be understood that by reversing the rotation of the rotor, the movable conducting element can be unwound from the gear 26 and rewound upon the stator 15, whereby it will be seen that the contact area 40 of the conductor 37 with respect to the di-electric 24 can be varied at will, thus securing any capacity desired within the range of 45 the instrument.

If it is desired to secure an extremely fine adjustment of the capacity, such adjustment can be obtained by an adjustment of the 50 screw head 28 to increase or decrease the friction between the conical portion 30 and the hub of the gear 26 which operates to vary the contact pressure between the movable conducting element and the di-electric, it being understood that as the friction is increased the conducting element will be slightly shortened in length so that during 55 the winding thereof about the stator it will more snugly engage the di-electric to increase the pressure exerted thereon.

From the foregoing operation, taken in conjunction with the accompanying drawings, it will be manifest that I have provided a condenser in which the variation in 60 capacity is not obtained by changing the air

gap between the conductors, nor by any variation in pressure between the two conductors to obtain the major variations in capacity. On the contrary, the variation in capacity is obtained solely by varying the contact area of the movable conducting element with respect to the di-electric. Consequently, the efficiency of the condenser is uniform throughout its rated range of capacity. Further, the rolling contact of the 70 movable conducting element with respect to the di-electric permits the variation in contact area without any friction being set up between the di-electric and conducting element, thereby preventing any damage to the 75 mica and thus indefinitely maintaining the original range of capacity. It is to be further noted that the conductors of the condenser are disposed in parallelism with respect to the axis of the dial so that their active surfaces are not parallel to the surface of the dial, as in the usual condensers, whereby the production of body capacity from the operator's body or hand is entirely eliminated. 80

Although I have herein shown and described only one form of variable condenser embodying my invention, it is to be understood that various changes and modifications may be made therein without departing from the spirit of the invention and the 85 spirit and scope of the appended claims.

I claim as my invention:

1. A variable condenser comprising a stationary conducting element, an annular di-electric surrounding and contacting with the conducting element, a flexible conducting element, a rotatable member about which the flexible conducting element is normally wound, means by which the rotatable member is movable bodily and concentrically 100 about the di-electric, and means for rotating the member about its own axis when bodily rotated by said means to wind or unwind the flexible conducting element on or off of the di-electric according as the member is bodily 105 rotated in one direction or the other.

2. A variable condenser as embodied in claim 1 wherein the last means comprises a gear fixedly associated with the di-electric, and a gear fixed to the rotatable member. 115

3. A variable condenser as embodied in claim 1 wherein the last means comprises a gear fixedly associated with the di-electric, a gear fixed to the rotatable member, and a dial mounted for rotation and connected to 120 the last mentioned gear for bodily rotating the latter.

4. A variable condenser comprising a stator of disk form, a conducting element on the periphery of the stator, a di-electric secured on the conducting element, a second conducting element secured at one end to the stator, a gear fixed to the stator, a rotor element, and a second gear rotatably mounted 125 on the rotor element, meshing with the 130

first gear and connected to the other end of the second conducting element.

5. A variable condenser as embodied in claim 4 wherein the mounting for the second gear comprises a screw including a shank, a head threaded into the rotor element, and a conical portion connecting the head and shank, the gear being journaled on the shank and conical portion.
10. 6. A variable condenser comprising a stator having slots therein, a stationary conducting element of annular form mounted on the periphery of the stator and having an extension extending into one of said slots, a di-electric of annular form having extensions extending into the other slot of the stator and surrounding and contacting with the conducting element, a movable conducting element comprising a strip of conducting material secured at one end between the ends of the di-electric, and means by which the second conducting element can be wound on or unwound from the di-electric to vary the capacity of the condenser.
25. 7. A variable condenser comprising a stator having slots therein, a stationary conducting element of annular form mounted on the periphery of the stator and having an extension extending into one of said slots, a di-electric of annular form having extensions extending into the other slot of the stator and surrounding and contacting with

the conducting element, a movable conducting element comprising a strip of conducting material secured at one end between the ends of the di-electric; a rotor mounted for rotational movement on the stator and including a dial, a reel rotatably mounted on the rotor and to which the other end of the movable conducting element is secured, and means operatively connecting the reel and the stator whereby upon rotation of the rotor in one direction or the other the reel will be rotated bodily and about its own axis to wind or unwind the movable conducting element thereon and to thus vary the area of contact between the conducting element and the di-electric.

8. A variable condenser comprising a stationary conducting element, a di-electric surrounding and contacting with the conducting element, a flexible conducting element, a rotatable member about which the flexible conducting element is normally wound, means by which the rotatable member is movable bodily about the di-electric, and means for rotating the member about its own axis when bodily rotated by said means to wind or unwind the flexible conducting element on or off of the di-electric according as the member is bodily rotated in one direction or the other.

HISAICH KIMURA.
